UNITED STATES PATENT OFFICE.

OLIVER C. CROMWELL, OF BALTIMORE, MARYLAND.

PROCESS OF MANUFACTURING A DRAFT-YOKE FOR RAILWAY-CAR DRAFT-RIGGING

1,125,665.

Specification of Letters Patent. Patented Jan. 19, 1911

Application filed June 7, 1913. Serial No. 772,218.

To all whom it may concern:

Be it known that I, OLIVER C. CROMWELL, a citizen of the United States, residing at Baltimore, in the State of Maryland, have 5 invented a certain new and useful Improvement in Processes of Manufacturing a Draft-Yoke for Railway-Car Draft-Rigging, of which the following is a full, clear, concise, and exact description, reference 10 being had to the accompanying drawings, forming a part of this specification.

My invention relates to a process of manufacturing a draft yoke for railway car draft rigging.

15 The object of my invention is to provide a cheap and easy process of manufacturing a draft yoke.

In the drawings forming a part of this specification, Figures 1 and 1^A are per-

20 spective views of billets of yoke material.

Fig. 2 is a perspective view of same, in which Fig. 1 is forged down to a bar and Fig. 1^A upset with enlarged ends. Fig.

25 3 is a perspective view showing the ends formed into T-heads. Fig. 4 is a perspective view showing the T-heads formed into U-shaped members. Fig. 5 is a perspective view showing the bar bent to form a yoke.

Fig. 6 is a perspective view showing the 30 limbs of the yoke in parallel arrangement, and the U-shaped ends in position for joining them together. Fig. 7 is a perspective view showing the U-shaped members joined into one piece. Fig. 8 is a perspective view

35 showing the completed draft yoke with lateral slots to receive the coupler key.

Referring to the drawings, 9 and 9^A illustrate the billets of material. With the exception of the ends of the billet 9 the same

40 is drawn preferably by forging to a bar comprising the strap 10 and having enlarged portion 11, or the billet, 9^A has the metal gathered at the ends, producing the strap 10, and having enlarged portion 11 at

45 ends, as illustrated in Fig. 2. The enlarged ends 11 are then flattened into T-heads 12,

12, the outer edges 13, 13 of the same being concaved, as illustrated in Fig. 3. The edges of the T-heads are then folded into U-shaped

50 members 14, 14, as illustrated in Fig. 4 of the drawings, and the bar 10 is then bent near its middle portion, the U-shaped mem-

bers at either end being folded toward each other, forming the upright member 15 of a draft yoke and the limbs 16, 16, as illustrated in Fig. 5 of the drawings. The limbs 16, 16 are then brought to a substantially parallel position, each side of one U-shaped member 14 engaging a side of the other U-shaped member 14, as illustrated in Fig. 6 of the drawings, the U-shaped members being in position to be joined together by forging or welding. The U-shaped members are then joined together to form the hollow yoke head 17, illustrated in Fig. 7 of the drawings. The yoke head is then provided with slots 18, 18 for the reception of a coupler key, thus forming the completed draft yoke illustrated in Fig. 8 of the drawings.

I claim:

1. A process of manufacturing a draft yoke comprising the drawing of a billet into a bar having enlarged ends, then flattening each end into a T-head, folding said T-heads into a U-shape, then bending said bar into a U-shape with the U-shaped members at either end thereof engaging each other, then joining said U-shaped members together forming a hollow yoke head.

2. A process of manufacturing a draft yoke comprising the drawing of a billet into a bar having enlarged ends, then flattening each end into a T-head, folding said T-heads into a U-shape, then bending said bar into a U-shape with the U-shaped members at either end thereof engaging each other, then joining said U-shaped members together forming a hollow yoke head, and slotting said yoke head.

3. A process of manufacturing a draft yoke comprising the drawing of a billet into a bar having enlarged ends, then flattening each end into a T-head and concaving the outer edge of each T-head, folding said T-heads into a U-shape, then bending said bar into a U-shape with the U-shaped members at either end thereof engaging each other, then joining said U-shaped members together forming a hollow yoke head.

OLIVER C. CROMWELL.

Witnesses:

CLEVELAND R. BEALMEAR,
M. GOLDBERG.

It is hereby certified that in Letters Patent No. 1,125,665, granted January 19, 1915, upon the application of Oliver C. Cromwell, of Baltimore, Maryland, for an improvement in "Processes of Manufacturing a Draft-Yoke for Railway-Car Draft Rigging," an error appears in the printed specification requiring correction as follows: Line 74, for the word "flattened" read *flattening*; and that the said Letters Patent should be read with this correction therein that the same may conform to the record of the case in the Patent Office.

Signed and sealed this 9th day of February, A. D., 1915.

[SEAL.]

J. T. NEWTON,

Acting Commissioner of Patents.
